UNITED STATES PATENT OFFICE

105,146

DESIGN FOR A KNOB FOR A GEAR SHIFT LEVER OR THE LIKE

John Sinko, Oak Park, Ill.

Application April 19, 1937, Serial No. 68,875

Term of patent 7 years

To all whom it may concern:

Be it known that I, John Sinko, a citizen of the United States, residing at Oak Park, county of Cook, and State of Illinois, have invented a new original, and ornamental Design for a Knob for a Gear Shift Lever or the like, of which the following is a specification, reference being had to the accompanying drawing, forming a part thereof, in which:

Figure 1 is a plan view of a knob for a gear

shift lever or the like, embodying the invention; and Fig. 2 an elevational view of the same.

The button is about one-third the diameter of the knob, and is of highly polished appearance. The device of applicant's design is also adapted to be used as a knob for a steering wheel bracket.

I claim:

The ornamental design for a knob for a gear shift lever or the like, as shown and described.

JOHN SINKO.
